(57) **CLAIM**

The ornamental design for an electronically controlled brake system unit, as shown and described.

DESCRIPTION

FIG. 1 is a front elevational view of an electronically controlled brake system unit showing the new design in full lines, with environmental association matter shown in broken lines for illustrative purposes only;

FIG. 2 is a right side elevational view thereof, with environmental association matter shown in broken lines for illustrative purposes only;

FIG. 3 is a top plan view thereof, with environmental association matter shown in broken lines for illustrative purposes only;

FIG. 4 is a bottom plan view thereof;

FIG. 5 is a rear elevational view thereof; and,

FIG. 6 is a left side elevational view thereof, with environmental association matter shown in broken lines for illustrative purposes only.

1 Claim, 6 Drawing Sheets

FIG. 1

FIG. 2

FIG. 3

FIG. 4

FIG. 5
